UNITED STATES PATENT OFFICE.

MAX BERKOWITZ, OF RICHMOND HILL, NEW YORK.

DESIGN FOR A VANITY-CASE.

58,869.

Specification for Design.

Patented Sept. 6, 1921.

Application filed January 10, 1921. Serial No. 436,372. Term of patent 3½ years.

To all whom it may concern:

Be it known that I, MAX BERKOWITZ, a citizen of the United States, residing at Richmond Hill, in the county of Kings and State of New York, have invented a new, original, and ornamental Design for Vanity-Cases, of which the following is a specification, reference being had to the accompanying drawing, forming part hereof, in which—

Figure 1, is a perspective view of a vanity case with the cover closed, showing my new design; and,

Fig. 2, is a perspective view of the vanity case with the cover open.

I claim:

The ornamental design for a vanity case, substantially as shown.

MAX BERKOWITZ.
